ROTATABLE INFLATABLE SANDER TOOL

Melvin J. Briggs, P.O. Box 92, Wakefield, R.I. 02880

Filed Apr. 10, 1969, Ser. No. 16,668

Term of patent 14 years

Int. Cl. D8—02

U.S. Cl. D37—1

FIG. 1 is a top perspective view of a rotatable inflatable sander showing my new design;

FIG. 2 is a top perspective view of a rotatable inflatable sander tool showing another form of my new design wherein the top plate is of larger radial extent and wherein the internal openings or vanes are of a proportionately larger size than as shown in FIG. 1;

FIG. 3 is a top perspective view of a rotatable inflatable sander tool showing still another form of my new design wherein the internal openings or vanes are of a larger proportional extent than as shown in FIG. 1;

FIG. 4 is a side elevational view of the tool shown in FIGS. 1 through 3; and

FIG. 5 is a bottom perspective view thereof.

I claim:

The ornamental design for a rotatable inflatable sander tool, substantially as shown.
